UNITED STATES PATENT OFFICE.

WILLIAM MILLS, OF BIRMINGHAM, AND WILLIAM MORGAN, OF BRISTOL, ENGLAND;
SAID MORGAN ASSIGNOR TO SAID MILLS.

FUSE AND THE LIKE FOR GRENADES, PROJECTILES, LAND-MINES, AND THE LIKE.

1,262,825.

Specification of Letters Patent. Patented Apr. 16, 1918.

Application filed December 23, 1916. Serial No. 138,640.

To all whom it may concern:

Be it known that we, WILLIAM MILLS and WILLIAM MORGAN, subjects of the King of Great Britain, residing at Bridge street west, 5 Birmingham, in the county of Warwick, England, and 45 Westbury road, Bristol, in the county of Gloucester, England, respectively, have invented certain new and useful Improvements in or Relating to Fuses and the 10 like for Grenades, Projectiles, Land-Mines, and the like, of which the following is a specification.

This invention comprises certain improvements in or relating to fuses and the like 15 for grenades, projectiles, land mines, and the like, and it has for its purpose to better protect Bickford type cord and like fuses from atmospheric conditions and to reduce the possibility of mis-fire to a minimum. With 20 this object in view the fuse end and the inflammable part thereof, is waterproofed and the waterproofing is effected in such a manner that the firing and combustion of the fuse is improved. With this object in view 25 we employ a waterproofing material which is of a highly inflammable character.

In a convenient embodiment of the present invention, we prepare a solution of 30 highly inflammable material, such as celluloid or nitrated cellulose dissolved in a suitable solvent, such as ether and alcohol mixture for the lower nitrated compound, and amyacetate for the more highly nitrated compounds. The end of a Bickford cord or 35 like time fuse is coated with this solution by any suitable process, and the applied solution may then be allowed to set. Or before the solution has been allowed to set the solutionized area may be dusted or otherwise 40 treated with gun powder. Afterward this gun powder may or may not be treated with a second coating of the solution.

In order that this invention may be clearly understood and readily carried into practice, 45 reference may be had to the appended explanatory drawing, which illustrates in section, and on an enlarged scale a Bickford cord time fuse treated according to the present invention.

50 *a* is the combustible fuse charge; *b* is the casing of the fuse, which may be of fabric or other appropriate material. To the end of such a fuse a layer or coating *c* of highly inflammable waterproofing material is applied, said coating being extended over the

sectional extremity of the casing *b*, as well as over the sectional extremity of the fuse charge *a*. When applying this first coating, a number of the fuses *a*, *b*, may be located side by side and retained in close contiguity with their extremities in a common plane, and the extremities may then be collectively treated with the coating *c*, as for instance by a brush or by spraying. The coated surfaces may then if desired be dusted or treated with meal or fine grain gun powder *d*, conveniently before the waterproofing material *c* has set or dried. After this treatment 60 the fuses may be separated from each other, and each fuse, or the end thereof, may be 65 dipped into the waterproofing solution so that the end of the fuse is thereby provided with a coating *e* of the waterproofing material. This second coating may alternatively be applied by a brush or by spraying. The 70 coating *e* may extend a suitable distance around the circumferential exterior of the fuse casing *b*. Or the entire fuse casing may if desired be coated with the waterproofing solution. Either extremity or both 75 80 extremities of the fuse may be treated according to the present invention.

Alternatively the gun powder may be applied at the same time as the solution by making a paste of the gun powder and the 85 solution and suitably treating the fuse with this paste.

The solution may be utilized in a number of ways for waterproofing or protecting from atmospheric conditions the fuse; for 90 instance, in the manufacture of the fuse the combustible contents thereof may be treated or impregnated with the waterproofing solution.

The invention is applicable to fuses adapted to be fired by a percussion cap or fuses adapted to be fired in any other applicable manner. In a fuse adapted, for instance, to be fired by virtue of the application of a suitable brimstone or like igniting firing portion at the extremity adapted to be ignited by friction, the brimstone or the like may be treated or impregnated with the waterproofing solution.

What we claim as our invention and desire to secure by Letters Patent is:—

1. A Bickford type cord or like time fuse such as set forth, which, or a part of which, has been coated with a waterproofing solution by any suitable process such as dipping 110

or by a brush or by spraying, and in which before the solution has been allowed to set, the solutionized area has been dusted or otherwise treated with meal gun powder, 5 which gun powder may or may not be treated with a second coating of the waterproofing solution.

2. A Bickford type cord or like time fuse, an entire end of which is covered with a 10 coating of waterproofing inflammable material, and which adheres directly to the fuse end.

3. A Bickford type cord or like time fuse,

an entire end of which has a coating of inflammable water-proofing material there- 15 upon adhering directly to the material of the fuse, said coating containing also particles of gunpowder.

In testimony whereof we affix our signatures in presence of two witnesses.

WILLIAM MILLS.

WILLIAM MORGAN.
